Primary Examiner — Susan Bennett Hattan*Assistant Examiner* — Charles Hanson(74) *Attorney, Agent, or Firm* — New River Valley IP Law, P.C.; Michele L. Mayberry(57) **CLAIM**

The ornamental design for a waistband, as shown and described.

DESCRIPTION

FIG. 1 is a front perspective view of a design for a waistband in accordance with the present invention;

FIG. 2 is a rear perspective view thereof;

FIG. 3 is a front elevation view thereof;

FIG. 4 is a rear elevation view thereof;

FIG. 5 is right side elevation view thereof;

FIG. 6 is a left side elevation view thereof; and,

FIG. 7 is a top plan view thereof.

The broken lines shown are included for the purpose of illustrating the unclaimed portions of the article that form no part of the claimed design.
